(57) CLAIM

The ornamental design for a makeup brush holder, as shown and described.

DESCRIPTION

FIG. 1 is a top, front and right side perspective view of a makeup brush holder showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a bottom, rear and left side perspective view thereof; and,
FIG. 9 is a top, rear, and left side perspective view showing the design in use holding two makeup brushes.
The dashed broken lines in FIG. 9 show makeup brushes that form no part of the claimed design.

1 Claim, 9 Drawing Sheets
